RADIATOR COVER

Thomas F. O'Connor, Jr., Hartford, Conn., assignor to The Vulcan Radiator Company, Hartford, Conn., a corporation of Connecticut

Application August 17, 1949, Serial No. 4,564

Term of patent 7 years

(Cl. D81—21)

To all whom it may concern:

Be it known that I, Thomas F. O'Connor, Jr., a citizen of the United States of America, residing at Hartford, in the county of Hartford and State of Connecticut, have invented a new, original, and ornamental Design for a Radiator Cover, of which the following is a specification, reference being had to the accompanying drawing, forming part thereof.

Fig. 1 is a front elevational view of a radiator cover embodying my new design.

Fig. 2 is a sectional view thereof on line 2—2 of Fig. 1.

Fig. 3 is a perspective view thereof, the right end being shown broken away for convenience of illustration.

I claim:

The ornamental design for a radiator cover, substantially as shown,

THOMAS F. O'CONNOR, JR.
